CONVEYER FOR SKEIN OR YARN DRIERS

Application filed October 24, 1929. Serial No. 402,257.

This invention relates to a new form of conveyer for handling material in skein form.

The object of the invention is to provide a conveyer for this type of material in which the poles employed for suspending or carrying the skeins are at all times permanently but movably attached to the conveyer proper.

Another object of the invention is to construct the conveyer and the skein-carrying poles in such a manner that the said poles may be moved to various angular positions relative to the conveyer, to facilitate the placing of the skeins on the poles and their removal therefrom.

Other objects of the invention and the construction thereof will be fully disclosed hereinafter, reference being had to the accompanying drawings, of which:

Fig. 1 is a side elevation of a conveyer made in accordance with the principles of the invention;

Fig. 2 is an enlarged side elevation of the conveyer shown in Fig. 1;

Fig. 3 is a transverse sectional elevation, taken on the line 3—3, Fig. 2; and

Fig. 4 is a plan view of the conveyer with the outer ends of the poles eliminated.

As shown in the drawings, the conveyer comprises a chain or other suitable conveying element 1. The chain 1, in the present instance, is composed of link-sections 2 and 3 pivotally connected together by transversely extending pintles 4, 4.

Each of the link-sections 2 comprising side bars 5, 5 and each of the link-sections 3 comprising side bars 6, 6 which are apertured at their respective ends for the reception of reduced portions 7, 7 of the pintles 4, whereby the side bars of the respective link-sections are laterally spaced. The pintles 4 are further reduced in diameter as indicated at 8, 8 for the reception of rollers 9, 9 which are rotatably mounted on the ends 8, 8 of the pintles 4 and adapted to ride on suitable rails, such as indicated at 10, 10 in Fig. 3, for supporting the conveyer.

On the outside of each of the side bar 5, 5 of the link-sections 2 and depending therefrom are located plates 11, 11 and on the

inside of the side bars 6, 6 of the link-sections 3 are provided similar depending plates 12, 12.

Extending transversely of the conveyer chain 1 and through the plates 11, 11 and 12, 12 respectively are pole-supporting elements or studs 15 which, as shown in Fig. 3, extend laterally beyond the depending plates 12, 12 as indicated at 16, the studs 15 being held in definite relation to the chain 1 by means of pins 17, 17 which extend diametrically through the studs 15 and beyond the outer faces thereof, intermediate the plates 12, 12, thereby preventing longitudinal movement of the studs 15 with respect to the conveyer chain 1.

Mounted on each of the laterally extending ends 16 of the studs 15 are tubular skein-carrying poles 20, in the outer end of each of which is located a closure cap 21 having an inwardly extending lug 22 adapted to receive one end of a wire or rod 23, the opposite end of the wire being connected to a tension spring 24, the opposite end of the spring 24 being connected to one of the pins 17 extending across the hollow or tubular stud 15.

The end of each of the poles 20 adjacent the conveyer chain 1 is flanged as indicated at 27, forming a bearing surface for the end of the pole 20 against the side of the supporting plate 11 or 12 as the case may be. In each instance a suitable washer 28 is placed between the inner side of the supporting plate and the pin 17, which prevents lateral movement of the stud 15 relative to the conveyer chain 1.

The conveyer chain is adapted to pass longitudinally through a suitable drying chamber diagrammatically illustrated at 30 in Fig. 1, the supporting rails 10, 10 being adapted to extend from one end of the drying chamber to the opposite end thereof or to points adjacent the sprocket wheels 31 and 32 disposed in any desired position adjacent the opposite ends of the drier. Any desirable means may be provided for driving the conveyer chain 1 so that the skeins placed on the poles 20 at one end of the drier will be conveyed through the drying chamber and

out through a suitable opening in the opposite end of the drier.

In placing the skeins on the poles or removing the skeins from the poles it has been found desirable to drop the outer end of the pole so that the pole will be in an inclined position with respect to its normal carrying plane, the pole being universally connected to the conveyer chain by the spring 24, whereby the operator having a number of skeins hanging over his arm, or having his arm extending through the center of the skeins to support the same, may grasp the outer end of the pole with the hand on which his skeins are supported and with the other hand transfer the skeins from his arm to the pole.

In removing the skeins from the pole this operation is reversed, the operator grasping the outer end of the pole with one hand and with the other hand sliding the skeins from the pole onto the arm with which the end of the pole is grasped.

Reference to Fig. 3 of the drawings will show that the construction described will permit of such universal movement of the pole 20 with respect to the conveyer chain 1, the inner end of the pole 20 telescoping with and being slidably mounted on the laterally projecting end 16 of the stud 15 is normally held against the supporting plate by the spring 24, but may be readily moved longitudinally until the inner flanged end 27 of the pole is brought to a position beyond the outer end of the extension 16 of the stud, whereupon the pole may be moved to any desired angle with respect to the stud and at the same time be permanently attached to the stud, by means of the spring 24. To return the pole 20 to its normal skein-carrying position the pole is raised, or otherwise moved, until it is substantially in axial alignment with the laterally extending portion 16 of the stud 15, whereupon the tension of the spring 24 will draw the pole 20 longitudinally inward over the end 16 of the stud until the flanged end 27 of the pole rests against the outer side of the supporting plate.

In the drawings the supporting plates 11 and 12 have been illustrated as independent members secured by rivets or other fastenings 32 to the side bars 5 and 6 of the carrying chain 1, but obviously these side bars may be so constructed that the supporting plates 11 and 12 would be formed as integral parts of the respective side bars, without departing from the spirit of the invention.

We claim:

1. In a skein conveyer, the combination of a conveying element, a pole extending laterally from and supported solely and at one end only by said conveying element, and means constantly connecting the said end of said pole to said conveying element and permitting universal movement of the pole relative to the conveying element.

2. In a skein conveyer, the combination of a conveying element, a pole extending laterally from and supported solely and at one end only by said conveying element, means constantly connecting the said end of said pole to said conveying element and permitting universal movement of the pole relative to the conveying element, and means for maintaining said pole rigidly in said laterally extending position relative to said conveying element. 70

3. In a skein conveyer, the combination of a conveying element, a pole extending laterally from and supported solely and at one end only by said conveying element, means constantly connecting the said end of said pole to said conveying element and permitting universal movement of the pole relative to the conveying element, and means for maintaining said pole rigidly in said laterally extending position relative to said conveying element but permitting longitudinal movement of the pole to permit of said universal movement subsequent thereto. 80

4. In a skein conveyer, the combination of a conveying element, a pole extending laterally from and supported solely and at one end only by said conveying element, means constantly connecting the said end of said pole to said conveying element and permitting universal movement of the pole relative to the conveying element, and means comprising a telescopic joint formed between the pole and the conveying element for maintaining said pole rigidly in said laterally extending position relative to said conveying element. 90

5. In a skein conveyer, the combination of a conveying element, a pole extending laterally from and supported solely and at one end only by said conveying element, means constantly connecting the said end of said pole to said conveying element and permitting universal movement of the pole relative to the conveying element, and means comprising a telescopic joint formed between the pole and the conveying element for maintaining said pole rigidly in said laterally extending position relative to said conveying element but permitting longitudinal movement of the pole to permit of said universal movement subsequent thereto. 100

6. In a skein conveyer, the combination of a conveying element, a pole extending laterally from and supported solely and at one end only by said conveying element, and means for rigidly but releasably supporting said pole in said laterally extending position relative to said conveying element. 110

7. In a skein conveyer, the combination of a conveying element, a pole extending laterally from and supported solely and at one end only by said conveying element, and means for rigidly but releasably supporting said pole in said laterally extending position 120

13

- relative to said conveying element, said pole being adapted for longitudinal movement relative to said conveying element for effecting said release.
- 5 8. In a skein conveyer, the combination of a conveying element, a pole extending laterally from and supported solely and at one end only by said conveying element, means for rigidly but releasably supporting said pole in said laterally extending position relative to said conveying element, and means for constantly but resiliently connecting said pole to said conveying element effective after said release is effected.
- 10 9. In a skein conveyer, the combination of a conveying element, a stud extending laterally from said conveying element, a pole telescopically coupled at one end to said stud and supported in a laterally extending position with respect to said conveying element by said stud.
- 15 10. In a skein conveyer, the combination of a conveying element, a stud extending laterally from said conveying element, a pole telescopically coupled at one end to said stud and supported in a laterally extending position with respect to said conveying element by said stud, and means for resiliently connecting said pole to said stud.
- 20 11. In a skein conveyer, the combination of a conveying element, a tubular stud extending laterally from said conveying element, a tubular pole telescopically coupled at one end to said tubular stud, and a spring extending through said tubular elements and having one end secured to the pole and the opposite end secured to the stud.
- 25 12. In a skein conveyer, the combination of a conveying element, a tubular stud extending transversely of the conveying element, a tubular pole adapted to each end of the tubular stud and extending laterally from the conveying element in opposite directions, a spring extending through each pole and into the stud and having one end connected to the pole and the opposite end connected to the stud.
- 30 13. In a skein conveyer, the combination of a conveying chain composed of a plurality of pivotally connected link sections, each link section comprising a pair of laterally spaced side bars, a stud extending transversely of and carried by the side bars of each link section, a pole adapted to telescopically fit the end of the stud and to extend laterally from the conveyer chain, wheels rotatably mounted on opposite sides of the conveyer chain, and tracks adapted to receive and support said wheels.
- 35 14. In a skein conveyer, the combination of a conveyer chain composed of a plurality of pivotally connected link sections, each link section comprising a pair of laterally spaced side bars, a hollow stud carried by said side bars and extending transversely of the link
- section, a tubular pole adapted to telescopically fit each end of the tubular stud, and a spring extending through each pole and into the stud, said spring having its ends respectively secured to the pole and the stud.
- 40 15. In a skein conveyer, the combination of a conveyer chain composed of a plurality of pivotally connected link sections, each link section comprising a pair of laterally spaced side bars, a hollow stud carried by said side bars and extending transversely of the link section, a tubular pole adapted to telescopically fit each end of the tubular stud, a spring extending through each pole and into the stud, said spring having its ends respectively secured to the pole and the stud, wheels rotatably mounted on each side of the conveyer chain, and rails adapted to receive and support said wheels.
- 45 16. In a skein conveyer, the combination of a conveyer chain composed of a plurality of link sections, each link section comprising a pair of laterally spaced side bars, pintles extending transversely of and pivotally connecting the said link sections, wheels rotatably mounted on said pintles at the opposite sides of said conveyer chain, a hollow stud carried by said side bars and extending transversely of the link section, a tubular pole adapted to telescopically fit each end of the tubular stud, and a spring extending through each pole and into the stud, said spring having its ends respectively secured to the pole and the stud.
- 50 17. In a skein conveyer, the combination of a conveyer chain composed of a plurality of pivotally connected link sections, each link section comprising a pair of laterally spaced side bars, a stud extending transversely of and carried by the side bars of each link section, a pole adapted to telescopically fit the end of the stud and to extend laterally from the conveyer chain, wheels rotatably mounted on opposite sides of the conveyer chain, and tracks adapted to receive and support said wheels.
- 55 18. In a skein conveyer, the combination of a conveyer chain composed of a plurality of pivotally connected link sections, each link section comprising a pair of laterally spaced side bars, a hollow stud carried by said side bars and extending transversely of the link
- 60 19. In a skein conveyer, the combination of a conveyer chain composed of a plurality of pivotally connected link sections, each link section comprising a pair of laterally spaced side bars, a hollow stud carried by said side bars and extending transversely of the link
- 65 20. In a skein conveyer, the combination of a conveyer chain composed of a plurality of pivotally connected link sections, each link section comprising a pair of laterally spaced side bars, a hollow stud carried by said side bars and extending transversely of the link
- 70 21. In a skein conveyer, the combination of a conveyer chain composed of a plurality of pivotally connected link sections, each link section comprising a pair of laterally spaced side bars, a hollow stud carried by said side bars and extending transversely of the link
- 75 22. In a skein conveyer, the combination of a conveyer chain composed of a plurality of pivotally connected link sections, each link section comprising a pair of laterally spaced side bars, a hollow stud carried by said side bars and extending transversely of the link
- 80 23. In a skein conveyer, the combination of a conveyer chain composed of a plurality of pivotally connected link sections, each link section comprising a pair of laterally spaced side bars, a hollow stud carried by said side bars and extending transversely of the link
- 85 24. In a skein conveyer, the combination of a conveyer chain composed of a plurality of pivotally connected link sections, each link section comprising a pair of laterally spaced side bars, a hollow stud carried by said side bars and extending transversely of the link
- 90 25. In a skein conveyer, the combination of a conveyer chain composed of a plurality of pivotally connected link sections, each link section comprising a pair of laterally spaced side bars, a hollow stud carried by said side bars and extending transversely of the link
- 95 26. In a skein conveyer, the combination of a conveyer chain composed of a plurality of pivotally connected link sections, each link section comprising a pair of laterally spaced side bars, a hollow stud carried by said side bars and extending transversely of the link
- 100 27. In a skein conveyer, the combination of a conveyer chain composed of a plurality of pivotally connected link sections, each link section comprising a pair of laterally spaced side bars, a hollow stud carried by said side bars and extending transversely of the link
